Des. 184,663
Patented Mar. 24, 1959

184,663

BURIAL VAULT

John R. Christensen, Burlingame, Calif., assignor to Christy Vault Company, Colma, Calif., a corporation of California

Application July 21, 1958, Serial No. 51,856

Term of patent 14 years

(Cl. D19—1)

FIG. 1

The sides of the burial vault not shown, are substantially the same in appearance as the sides shown.

I claim:

The ornamental design for a burial vault, substantially as shown and described.
